UNITED STATES PATENT OFFICE

169,239

BOTTLE

Chadbourn L. Dillon, Los Angeles, Calif., assignor to Rehrig Manufacturing Co., Los Angeles,
Calif., a partnership

Application June 6, 1952, Serial No. 20,058

Term of patent 3½ years

(Cl. D58—8)

To all whom it may concern:

Be it known that I, Chadbourn L. Dillon, a citizen of the United States of America, residing in the city of Los Angeles, in the county of Los Angeles, State of California, have invented a new, original, and ornamental Design for a Bottle, of which the following is a specification, reference being had to the accompanying drawing forming a part thereof.

Fig. 1 is a perspective view of a bottle drawn to a reduced scale, showing my new design;

Fig. 2 is an elevational view thereof; and

Fig. 3 is a top plan view thereof.

I claim:

The ornamental design for a bottle, substantially as shown.

CHADBOURN L. DILLON.
